Inventor,
John Dudek

By Warren D. House,
His attorney.

UNITED STATES PATENT OFFICE.

JOHN DUDEK, OF CAMPBELL, NEBRASKA.

CAP-WRENCH.

1,363,316.

Specification of Letters Patent. Patented Dec. 28, 1920.

Application filed July 12, 1919. Serial No. 310,303.

To all whom it may concern:

Be it known that I, JOHN DUDEK, a citizen of the United States, residing at Campbell, in the county of Franklin and State of 5 Nebraska, have invented a certain new and useful Improvement in Cap-Wrenches, of which the following is a specification.

My invention relates to improvements in cap wrenches.

10 The object of my invention is to provide a cap wrench for tightening and loosening the screw cap of an ordinary Mason jar, which is simple in construction, cheaply manufactured, durable, not liable to get out 15 of order, and which is efficient in operation.

The novel features of my invention are hereinafter fully described and claimed.

In the accompanying drawing which 20 illustrates the preferred embodiment of my invention,

Figure 1 is a perspective view of my improved cap wrench.

Fig. 2 is a top view of the same.

Fig. 3 is a central vertical sectional view 25 of the wrench, shown applied to an ordinary screw cap on a Mason jar, a portion of the latter being shown.

Similar reference characters designate 30 similar parts in the different views.

1 and 2 designate respectively two jar members, each provided with an arcuate substantially semi-circular downwardly extending flange 3, preferably provided on its inner side with corrugations 4 and adapted 35 to clamp one side of an ordinary screw cap 5 of a common Mason jar 6. The members 1 and 2 are adapted to rest upon the top of the cap 5 and are pivoted together at one 40 side of their centers and at the inner side of and adjacent to their peripheries by a vertical pin 7.

Respectively attached to the upper sides 45 of the jaw members 1 and 2, by any suitable means, such as rivets 8, are two handles 9, preferably of channel form and having their channels at their inner sides. The handles 9 where they are attached to the jaw members are doubled and flattened. The handles extend outwardly from the opposite side of the centers of the jaw members to the side in which the pivot 7 is located.

Each handle 9 is depressed inwardly 50 from its outer side to form a transverse bridge portion 10, the sides of which are cut through so that an opening is formed

longitudinally between each bridge portion 10 and the inner side or bottom of the adjacent channel.

A bow spring 11, preferably of round wire 60 having a central coil 12, has its end portions extending respectively through the openings formed by the bridge portions 10, said bridge portions being afterward set down, that is forced outwardly, so as to form kinks 13 in 65 the spring 11, whereby the spring is held firmly clamped to the handles 9.

By providing the channels at the inner sides of the handles 9, a space is provided to receive the coil 12 of the spring, when the 70 handles 9 are forced nearly together when in the clamping position.

By providing the pivot 7 at the inner side of and closely adjacent to the peripheries of the jaw members 1 and 2, very great leverage 75 is effected by the jaw members at the portions of the cap where the clamping action is most efficient.

I do not limit my invention to the structure shown and described, as many modifications, within the scope of the appended 80 claims, may be made without departing from the spirit of my invention.

What I claim is:—

1. A cap wrench comprising two jaw 85 members adapted to rest upon the top of a jar cap and provided respectively with two downwardly extending arcuate flanges adapted to respectively clamp opposite sides of the cap, the jaw members being pivoted to each other at one side of their centers and at the inner side of and adjacent to their peripheries, two handles respectively attached to said members and extending outwardly at the opposite side of their centers, 90 each of said handles having a channel on its inner side, and a depressed portion at its outer side which forms a bridge at the inner side and in the channel of the handle, and a spring having its ends respectively 100 clamped between said bridges and the inner sides of said channels arranged to force the handles apart.

2. A cap wrench comprising two jaw members hinged together and arranged to 105 respectively clamp opposite sides of a jar cap, two channel handles respectively attached to said jaw member, the channels being at the inner sides of said handles, each handle having a bridge portion depressed into the channel of the handle from the outer side thereof, the sides of the bridge 110

- being cut away to form an opening between the outer side of the bridge and the inner side of the channel, and a spring having its ends extending respectively through said 5 openings between said bridges and the inner sides of said channels, the bridges after the insertion of said spring being set down to form kinks in the spring, the tension of the spring serving to force the handles apart.
- 10 3. A cap wrench comprising two jaw members arranged to respectively clamp opposite sides of a jar cap and pivoted to each other at the inner side of and adjacent to the peripheries and at one side of the centers 15 of said members, two channel handles respectively secured to said jaw members and

extending outwardly at the opposite side of said centers and having their channels at their inner sides, each handle having a bridge portion forced inwardly from its outer side beyond the inner side of the channel, the sides of the bridge portion being cut through so as to form a longitudinal opening between the bridge portion and the inner side of the channel, and a bow spring 20 having its ends respectively mounted in said openings, the bridge portions being set down to form kinks in the spring, the spring being arranged to force said handles apart.

In testimony whereof I have signed my 30 name to this specification.

JOHN DUDEK.
